UNITED STATES PATENT OFFICE.

HENRY O. HAMILTON, OF CHICAGO, ILLINOIS, ASSIGNOR TO H. & F. MFG. CO., OF CHICAGO, ILLINOIS, A CORPORATION OF ILLINOIS.

CHANGEABLE EXHIBITOR.

1,179,096.

Specification of Letters Patent.

Patented Apr. 11, 1916.

Application filed March 15, 1915. Serial No. 14,301.

To all whom it may concern:

Be it known that I, HENRY O. HAMILTON, a citizen of the United States of America, and a resident of Chicago, in the county of Cook, State of Illinois, have invented certain new and useful Improvements in Changeable Exhibitors, of which the following is a specification.

This invention relates to that type of changeable exhibitors in which two series or sub-packs of display cards are disposed within a suitable containing housing, the card from the front of one sub-pack being removed in a serial manner to the front of a companion sub-pack, and in due order the card at the rear of the last mentioned sub-pack is moved to the rear of the first mentioned sub-pack. Incidentally to such shifting of the cards from one sub-pack to the other, the said sub-packs have lateral movement bodily, in the case of one sub-pack in a forward direction and in the case of the other sub-pack in a rearward direction. And the present improvement has for its object to provide a simple and efficient structural formation and combination of parts whereby the above described functions and operations are automatically attained in a serial manner, all as will hereinafter more fully appear.

In the accompanying drawings:—Figure 1, is a front elevation, partly sectioned, illustrating the general arrangement of parts, in the present invention. Fig. 2, is a detail perspective view of the operating mechanism by which the display cards are serially shifted from one sub-pack to the other. Fig. 3, is an enlarged detail horizontal section on line $x-x$, Fig. 1, illustrating the shifting mechanism at the front of the machine. Fig. 4, is a detail perspective view of one of the framed display cards and the associated abutment member for a sub-pack of said cards. Fig. 5, is an enlarged detail section of a marginal portion of a framed display card.

Similar reference numerals indicate like parts in the several views.

Referring to the drawings, 1 designates the main frame or housing of the exhibitor, preferably of the skeleton metal form shown.

2 and 3 designate upper and lower tracks or slideways secured to the frame 1 and extending longitudinally of the same from end to end. Each of said tracks comprises a pair of L shaped rails, spaced apart trans-

versely to correspond with the thickness of the sub-packs of display cards used, and suitably connected together by transverse connecting webs or bars.

4 designates the display cards, above referred to, and having a detail construction hereinafter described. Said cards are disposed in the tracks 2, 3, in two sub-packs as shown, and with one sub-pack containing a less number of cards than the other sub-pack, preferably one card less, and so that the shifting of a card from one sub-pack to the other may be attained in a ready and accurate manner by the mechanism of the present invention.

Each display card will preferably comprise a main central web or film and a marginal frame 5, formed of channel bars or rails of metal or like material connected together to form a rectangular structure, the top bar or rail of the structure being open to permit an introduction of the main central web into position in the frame.

6 designates a U shaped spring clip fitting over the top edge of the web or film aforesaid, and having out-turned flanges or lips 7 at the free ends of the clip which are adapted to engage beneath the lower edge of the upper rail or bar of the marginal frame 4, to hold said web or film in place. With the described construction the clip 6 is pushed downward along with the web or film aforesaid, the natural resiliency of the parts of the aforesaid upper rail or bar permitting said rail parts to spread apart and admit a passage of the aforesaid out-turned flanges 7.

8 designates longitudinal shoes, preferably associated with the upper and lower bars of the marginal frame 5, aforesaid, and each having an angular formation 9 at one end, as shown in Figs. 3 and 4, for the purpose hereinafter set forth in the operation of the mechanism.

10 designates counterpart transverse stop bars secured to the respective ends of the main frame 1 and arranged in the path of the series of display cards and adapted to position the same in the described sub-packs. In the preferred construction shown in Figs. 1 and 4, the stop bars 10 are detachably secured to the main frame 1 by open ended recesses and coacting studs in connection with hinged braces 11, by which said stop bars are normally supported in proper position.

12 and 13 designate a pair of counterpart longitudinally reciprocating cross-heads disposed respectively to the front and rear of the exhibitor and preferably guided in their movement by suitable slides preferably consisting of pairs of upper and lower guide rods 14 secured in spaced relation to the main frame 1, as shown.

15 and 16 designate front and rear pull-hooks individually pivoted to the respective cross-heads 12, 13, aforesaid, with their bent or hook shape ends 17 adapted for operative engagement with the rear end of the next adjacent display card 4 to effect a shifting movement of the same in the operation of the exhibitor.

18 and 19 designate springs associated with the respective pull-hooks, 15, 16, and adapted to yieldingly force the hook-shape ends 17 thereof toward their engaging position with the display cards. In the preferred construction shown in Figs. 2 and 3, the springs, 18, 19 are fixed on the pull-hooks 15, 16, with their free and resilient ends adapted to slide upon the adjacent faces of the lower tracks 3, before described. And with a view to permit independent longitudinal adjustment of the pull-hooks 15, 16, in the proper timing of the mechanism, said pull-hooks are pivotally carried on bracket plates 20, secured in a longitudinally adjustable manner to the cross-heads 12, 13, by elongated slots 21 and attaching screws, as shown in Figs. 2 and 3.

35 In the present invention the respective cross-heads 12 and 13 are spaced apart longitudinally in addition to the transverse spaced relation heretofore described, with a view to attain the requisite longitudinal shifting movement of the display cards with a minimum stroke of their operating cross-heads 12, 13. Simultaneous movement is imparted to the aforesaid cross-heads 12, 13, by a motor 22, and intermediate connections 40 as follows:—23 designates a countershaft having pulley and belt connection 24 with the shaft of the motor 22, and provided with a screw or worm 25 having operative engagement with a worm-wheel 26, on a secondary countershaft 27, journaled in suitable bearings on the main frame 1. In the preferred construction, said bearings are formed in the end heads of a tank or vessel 28 adapted to contain a quantity of lubricating oil, in which the aforesaid worm-wheel 26 and worm 25 are immersed with a view to eliminate undue friction and wear between said parts.

29 designates crank arms secured to the 60 respective ends of the secondary countershaft 27 aforesaid, and adapted for operative connection with the cross-heads 12, 13, by intermediate connections as follows:—30 designates pairs of longitudinally spaced pivoted links pivoted at their lower ends to

the main frame 1 and connected together at their upper ends by intermediate connecting links 31.

32 designates studs or rollers on the sides of the respective connecting links 31, having operative engagement in vertically elongated slots or openings 33 in the cross-heads 12, 13, and adapted to impart longitudinal reciprocation to said cross heads in synchronism with the oscillation of the links 30, 75 aforesaid. In such operation the studs or rollers 32 have vertical travel in the slots or openings 33, during their longitudinal travel in either direction.

34 designates pitman bars or links operatively connecting the pivoted links 30 with the crank arms 29 of the secondary countershaft 27 above described.

The operation of the mechanism is as follows:—Constant longitudinal reciprocation 85 is imparted to the cross-heads 12, 13, by the motor 22, through the intermediate connections above described. As the cross-head 12 nears the limit of its movement to the right, in the drawings, its pull hook 15 engages the edge of the adjacent display card 4 of the sub-pack of display cards to the right, and in a succeeding movement of said cross head 12 said display card is carried to the left. In such movement of the cross-head 12 and display card 4 to the left, the leading inclined ends 9 of the shoes 8 of said display card, rides before the inclined ends 9 of the shoes 8 of the display card 4 of the sub-pack of display cards to the left, 90 which is in alinement with the above mentioned display card of the sub-pack to the right, to automatically move said display card of the sub-pack to the left, in a transverse and rearward direction and take the 100 place thereof in said sub-pack to the left. With the cross-head 12 at the end of its stroke to the left, the cross-head 13 is also at the end of its stroke to the left with its pull-hook 17 moved into engagement with 105 the edge of the adjacent display card 4 of the sub-pack of display cards to the left, said display card being at the side opposite to that above described in the operation of the cross-head 12. In a succeeding movement of the cross-head 13, said display card is carried to the right, and in such movement the leading inclined ends of the shoes 8 of said display card rides behind the inclined ends of the shoes 8 of the display 110 card 4 of the sub-pack of display cards to the right, which is in alinement with the above mentioned display card of the sub-pack to the left, to automatically move said display card of the sub-pack to the right 115 in a transverse and forward direction and take the place thereof in sub-pack to right.

In the above described operation, the series of display cards have intermittent movements as follows:—first, longitudinally to 120

the left; second, transversely in a rearward direction toward the back of the sub-pack of cards to the left; third, longitudinally to the right and from the rear of the sub-pack, 5 to the left, to the rear of the sub-pack to the left, and fourth, transversely and in a forward direction toward the front of the sub-pack of cards to the right.

Having thus fully described my said invention what I claim as new and desire to secure by Letters Patent, is:—

1. In a changeable exhibitor, the combination of a main frame, a longitudinally disposed track adapted to contain two alined 15 sub-packs of display cards, a pair of cross-heads adapted for longitudinal reciprocation and having card engaging means individual to front and rear of the sub packs of cards and adapted to shift a card from the front of one sub-pack to the front of the other sub-pack and from the rear of one sub-pack to the rear of the other sub-pack, and means for imparting reciprocation to said cross-heads, the same comprising a secondary countershaft, crank arms on said countershaft, pairs of pivoted links connected together at one end by connecting links, operative means between said connecting links and the cross-heads aforesaid, and pitman connections between the pivoted links and the crank arms aforesaid, substantially as set forth.

2. In a changeable exhibitor, the combination of a main frame, a longitudinally disposed track adapted to contain two alined 25 sub-packs of display cards, a pair of cross-heads adapted for longitudinal reciprocation and having card engaging means individual

to front and rear of the sub-packs of cards and adapted to shift a card from the front 40 of one sub-pack to the front of the other sub-pack and from the rear of one sub-pack to the rear of the other sub-pack, said cross-heads having individual vertically elongated slots, a pair of connecting links having studs 45 in operative engagement with said elongated slots, pairs of pivotal links carrying said connecting links, and means for imparting simultaneous movement to said pivoted links, substantially as set forth. 50

3. In a changeable exhibitor, the combination of a main frame, a longitudinally disposed track adapted to contain two alined 55 sub-packs of display cards, a pair of cross-heads adapted for longitudinal reciprocation and having card engaging means individual to front and rear of the sub-packs of cards and adapted to shift a card from the front of one sub-pack to the front of the other sub-pack and from the rear of one sub-pack to 60 the rear of the other sub-pack, said cross-heads having individual vertically elongated slots, a pair of connecting links having studs in operative engagement with said elongated slots, pairs of pivoted links carrying said connecting links, pitman links connected to the pair of pivoted links aforesaid, and a countershaft having crank arms operatively connected to said pitman links, 65 substantially as set forth. 70

Signed at Chicago, Illinois, this 6th day of March, 1915.

HENRY O. HAMILTON.
